175,743

VENDING CART

Earl F. Rutan, Pound Ridge, N. Y.

Application February 21, 1955, Serial No. 34,585

Term of patent 14 years

(Cl. D14—3)

Fig. 1 is a view in perspective of a vending cart embodying by new design.

Fig. 2 is a side elevational view thereof with the side opposite this side being substantially similar to the side shown.

Fig. 3 is an end view of the instant device.

Fig. 4 is a top view of said design.

I claim:

The ornamental design for a vending cart, as shown.

References Cited in the file of this patent

UNITED STATES PATENTS

D. 158,853	Gray	June 6, 1950
D. 166,577	Smey	Apr. 22, 1952